COMBINATION COUPLER

Frederic Meier, Chicago, Ill., and Chester H. Rittenhouse, Hobart, Ind., assignors to Carnegie-Illinois Steel Corporation, a corporation of New Jersey

Application November 5, 1946, Serial No. 707,902

4 Claims. (Cl. 213—112)

1

This invention relates to a combination coupler for railroad cars and the like. In the open hearth departments of steel mills, three types of railroad cars are used: ingot buggies, charging box buggies and standard railroad cars. The railroad cars and some of the buggies are equipped with standard knuckle type couplers and the remaining buggies are equipped with link and pin type couplers. The locomotives used for moving these cars must be equipped to couple to either type of coupler. Several schemes have been tried to permit coupling of either type of couplers, but none have proved to be entirely satisfactory prior to this invention.

It is an object of this invention to provide a combination coupler for selectively coupling to either a standard railroad knuckle type coupler or a link and pin type coupler.

Another object is to provide such a coupler in which the two types of couplers are easily and quickly interchangeable.

Still another object is to provide such a coupler in which no parts need be removed to permit functioning of any other part and in which the coupler out of action will not interfere with the functioning of the one in use.

These and other objects will be more apparent after referring to the following specification and attached drawings, in which:

Figure 1 is a plan view of the coupler connected to a car equipped with a standard knuckle type coupler;

Figure 2 is a view similar to Figure 1, but showing the coupler connected to a car equipped with a link and pin type coupler; and

Figure 3 is an elevation of the coupler connected to a car equipped with a link and pin type coupler.

Referring more particularly to the drawings, the reference numeral 2 indicates a railroad car provided with a standard railroad knuckle type coupler 4. The coupler 4 is fastened by means of a pin 6 to a drawhead 8 which is provided with a pocket 10 for receiving the coupler 4. The drawhead 8 is received in a T-shaped pocket 12 in the car 2. This mounting is that commonly used in railroad cars. The combination coupler of my invention is mounted on a safety car 14 which is fastened to a locomotive. It will be understood that the combination coupler could be fastened to any car or locomotive in place of the coupler commonly used. The T-shaped head 18 of a drawhead 20 is fastened to the car 14. The outer end of the drawhead 20 is provided with a pocket 22 for receiving the shank 24 of a standard rail-

road knuckle type coupler 26. Bosses 28 and 30 are provided on the top and bottom surfaces of the drawhead 20 and extend beyond the top and bottom, respectively, of the coupler 26. A hole 32 extends vertically through the bosses and the drawhead. A U-shaped yoke 34 extends from the bosses outwardly beyond the coupler 26 and is provided with a slot 36 in its outer end in which is received a link 38 of a link and pin type coupler. Link 38 is fastened to the yoke 34 by means of a pin 40. The inner end of the yoke 34 is provided with aligned openings 42 and 44 which are in alignment with the opening 32 in the drawhead 20. A pin 46 extends through the aligned openings 32 and 44 and fastens the coupler 26 and the yoke 34 to the drawhead 20. The connecting pin 46 may be given additional outboard support by welding a bracket 48 to the car 14 with the free end of the bracket extending below the boss 30 and being provided with an opening 50 for the pin 46. The yoke 34 is permitted to swing from its operative position in which its center line is on the center line of the car 14 to its inoperative position shown in Figure 1. A stop 52 is provided on the drawhead 20 for limiting the movement of the yoke 34 to its operative position shown in Figure 2 and a second stop 54 is provided on the drawhead 20 to limit the movement of the yoke 34 to its inoperative position shown in Figure 1. Cooperating holes 56 and 58 are provided in the drawhead and yoke, respectively, for receiving a pin 60 which locks the yoke 34 in its inoperative position.

From the foregoing, it will be seen that the coupler 26 may be fastened to the coupler 4 by merely swinging the yoke 34 to the inoperative position and locking it in place by means of the locking pin 60 as shown in Figure 1. In this position, it will be noted that clearance 62 is provided between the coupler 4 and the yoke 34 and that clearance 64 is provided between the car 2 and the yoke 34.

Figure 2 shows the coupler connected to a railroad car 2' provided with a drawhead 8' which has a pocket 10' therein for receiving the link 38. The drawhead 8' is fastened in a T-shaped pocket 12' in the car 2'. When it is desired to connect the car 14 to the car 2', the pin 60 is removed and the yoke 34 and the link 38 is swung to the center line of the car. In this position, clearance 66 is provided between the coupler 26 and the yoke 34. The end of link 38 is received in the pocket 10' and a pin 6' is inserted through aligned openings in the drawhead 8' and link 38 to hold the cars together.

While one embodiment of our invention has been shown and described, it will be apparent that other adaptations and modifications may be made without departing from the scope of the following claims.

We claim:

1. A combination coupler for connecting a railroad car or the like selectively to a car provided with a railroad knuckle type coupler or a car provided with a link and pin type coupler, which combination coupler comprises a drawhead fastened to said first named railroad car, a railroad knuckle type coupler fastened to said drawhead, a yoke pivotally mounted on said drawhead and extending outwardly therefrom beyond said last named coupler, said yoke surrounding said last named coupler and being movable in a horizontal plane therearound from inoperative to operative position, a link fastened to said yoke and extending outwardly therefrom, stop lugs on said drawhead for limiting the swing of the yoke to its operative and inoperative positions, and means for holding the yoke in its inoperative position.

2. A combination coupler for connecting a railroad car or the like selectively to a car provided with a railroad knuckle type coupler or a car provided with a link and pin type coupler, which combination coupler comprises a drawhead fastened to said first named railroad car, a railroad knuckle type coupler fastened to said drawhead, aligned bosses on the top and bottom surfaces of said drawhead, a U-shaped yoke extending from said bosses outwardly beyond said last named coupler and pivotally mounted on said drawhead, a link fastened to said yoke and extending outwardly therefrom, stop lugs on said drawhead for limiting the swing of the yoke to its operative and inoperative positions, and means for holding the yoke in its inoperative position.

3. A combination coupler for connecting a railroad car or the like selectively to a car provided with a railroad knuckle type coupler or a car provided with a link and pin type coupler, which combination coupler comprises a drawhead fastened to said first named railroad car, said drawhead having a pocket in its outer end, a railroad knuckle type coupler having its shank extending into said pocket, means for fastening said last named coupler to said drawhead, aligned bosses on the top and bottom surfaces of said

drawhead, said bosses and drawhead having an opening extending therethrough, a U-shaped yoke extending from said bosses outwardly beyond said last named coupler, said yoke having a slot in its outer end, a link fastened in said slot and extending outwardly therefrom, said yoke having openings therein aligned with the openings in said bosses and drawhead, and a pin passing through said openings for pivotally supporting said yoke on said drawhead.

5. A combination coupler for connecting a railroad car or the like selectively to a car provided with a railroad knuckle type coupler or a car provided with a link and pin type coupler, which combination coupler comprises a drawhead fastened to said first named railroad car, said drawhead having a pocket in its outer end, a railroad knuckle type coupler having its shank extending into said pocket, means for fastening said last named coupler to said drawhead, aligned bosses on the top and bottom surfaces of said drawhead, said bosses and drawhead having an opening extending therethrough, a U-shaped yoke extending from said bosses outwardly beyond said last named coupler, said yoke having a slot in its outer end, a link fastened in said slot and extending outwardly therefrom, said yoke having openings therein aligned with the opening in said bosses and drawhead, a pin passing through said openings for pivotally supporting said yoke on said drawhead, stop lugs on said drawhead for limiting the swing of the yoke to its operative and inoperative positions, and means for holding the yoke in its inoperative position.

FREDERIC MEIER.

CHESTER H. RITTENHOUSE.
